UNITED STATES PATENT OFFICE.

JOSEPH L. GRAY, OF FORT WORTH, TEXAS.

DESIGN FOR A VALVE-FLOAT.

48,373.

Specification for Design.

Patented Jan. 4, 1916.

Application filed January 30, 1915. Serial No. 5,331. Term of patent 14 years.

To all whom it may concern:

Be it known that I, JOSEPH L. GRAY, a citizen of the United States, residing at Fort Worth, in the county of Tarrant and State of Texas, have invented a new, original, and ornamental Design for Valve-Floats, of which the following is a specification, reference being had to the accompanying drawing, forming part thereof.

Figure 1 is a bottom view of the float. Fig. 2 is a section therethrough.

I claim:—

The ornamental design for a valve float, as shown.

JOSEPH L. GRAY.

Witnesses:

G. N. SMITH,
H. MAX JEWELL.
